BLOTTER PAD AND THE LIKE

Franklin M. de Beers, Glencoe, Ill.

Application January 22, 1940, Serial No. 315,050

2 Claims. (Cl. 120—24)

- This invention relates to improvements in blotter pads and the like, such as are widely used on office desks and in similar locations. Such blotter pads are generally provided with corner plates 5 or the like, under which the corners of the blotter proper may be slipped so as to hold said blotter in place on the pad. Such blotter may then be readily removed and replaced from time to time as necessary.
- 10 In the conduct of most office businesses many memoranda and other papers are handled which it is desirable to place in some location where they will be temporarily available with convenience, and these corner plates or the like of the 15 blotter pad constitute a handy receptacle under which such papers and memoranda may be slipped. However, the capacity of such plates to hold such papers and memoranda is very limited, so that frequently an excessive number of such 20 papers is forced thereunder, and a very unsightly and bulky blotter pad corner is produced. Furthermore, such excessive loading of such corner pads results in injury or damage to the papers and memoranda, and sometimes loss of important 25 papers, etc. Not only are the foregoing objections true, but also any such papers and memoranda stuck under the corner plates of the blotter pad are so hid that they cannot be read except after removing them from the corner plates bodily.
- 30 This in turn entails damage to the papers, confusion, and sometimes loss of some of them.
- It is the main object of the present invention to provide, in conjunction with the usual corner plates of the blotter pad, edge supports extending 35 along the edges of the blotter pad, and so formed that such memoranda and other papers and cards, and the like may be slipped thereunder, such edge supports being provided along one or more of the edges of the blotter pad, and there- 40 by providing an elongated support having capacity to receive several times as many such memoranda etc., as can be accommodated under the corner plates themselves. Thus, for example, by providing such edge supports along the back 45 and side edges of the blotter pad I am able to provide approximately fifty-three (53) inches of space for accommodation of such papers and memoranda, in the case of a blotter pad of usual form and size.
- 50 It is a further object of the invention to provide such edge supports of transparent material such as Celluloid or the like, so that the papers and memoranda received thereunder shall be visible through the edge support and without having 55 to actually remove the papers and memoranda

therefrom. This will result in many advantages which are manifest.

A further object is to make these edge supports removable bodily from the corner plates of the blotter pad, so that they may be set into 5 place or removed from the blotter pad without any change in construction of the blotter pad itself. This will also make it possible to provide these edge supports as separate units or parts distinct from the blotter pad itself, and which 10 may be set into place in blotter pads already in service. In other words, by reason of this feature it is possible to sell and deliver a set of these edge supports to an owner of a blotter pad, and he in turn may set them into place in his blotter 15 pad without difficulty.

A further object of the invention is to so form these edge supports that they may be readily made from moulded or formed material, such as Celluloid or the like. This may be secured in 20 sheet form and cut to proper sizes and shapes and then formed by heat treatment into the edge supports herein disclosed.

Other objects and uses of the invention will appear from a detailed description of the same, 25 which consists in the features of construction and combinations of parts hereinafter described and claimed.

In the drawing:

Figure 1 shows a top face or plan view of a 30 typical blotter pad having applied thereto typical edge supports embodying features of my present invention;

Figure 2 shows a longitudinal section on the line 2—2 of Figure 1, looking in the direction of 35 the arrows;

Figure 3 shows a plan view of one of the edge supports removed from the blotter pad plates;

Figure 4 shows on enlarged scale (substantially full scale) one corner plate and the adjacent portion of the blotter pad, with the adjacent end portions of the edge supports set under the said corner plate; and

Figure 5 shows a section on the line 5—5 of Figure 4, looking in the direction of the arrows. 45

The blotter pad proper is designated by the numeral 10. It is generally made of stiff cardboard or other suitable material, and may be suitably covered according to the desired finish. The corners of this blotter pad are provided with 50 the corner plates 11, 12, 13 and 14. These are generally, as shown, of diagonal form, being semi-squares divided diagonally at an angle of forty-five degrees. Each of these corner plates is suitably secured to the corner edges of the blotter 55

pad base, and the details of such connection are not a portion of the present invention. It may be stated, however, that such connections of the corner plates are so made that the corner plates 5 are supported slightly above the surface of the body of the blotter pad, so that a blotter sheet 15 may have its corners readily slipped under these corner plates, and be held in place thereby. This is general practice at the present time. Due 10 to this fact, also, it has been customary to use these corner plates as receptacles for such miscellaneous papers and memoranda as already referred to.

According to my present invention I provide 15 one or more edge supports such as 16, 17, and 18 along the edges of the blotter pad, and extending between the said corner plates, and supported by such corner plates, generally in removable manner. A convenient arrangement is that 20 shown, in which these edge supports are in the form of strips of sheet Celluloid or the like, each of a width approximately one-half the edge dimension of one of the corner plates, so that two such edge strips, meeting at the position of the 25 corner plate, will come properly together. Furthermore, these strips may be readily formed with their inwardly facing edges doubled over as shown at 19 (see Figure 5 in particular), thereby reinforcing such edges, and also providing a more 30 finished and pleasing appearance, and also, as will be evident, serving to provide a better contact with any papers or memoranda set into place beneath these edge strips. For this purpose, such folded edge portions of the strips 35 should face downwardly as shown. Furthermore, it is desirable that the outwardly facing edge of each of these strips be bent or formed downwardly as shown at 20 (see Figure 5 in particular), so that a back stop is thereby provided to 40 prevent the papers or memoranda from being forced clear past the edge strips, with corresponding objectionable results. It is noted that when using such material as Celluloid or the like, a flat strip thereof may be readily bent and formed 45 into the desired formation for the present use, and as shown in Figure 5 in particular, by first heating the sheet Celluloid, and then suitably bending and forming it while still hot.

The ends of these edge strips are set beneath 50 the corner plates of the blotter pad. For such purpose it will be found that such strips have sufficient flexibility to be bent slightly to enable their end portions to be so set into place; and then due to the reinforcing of the strips occasioned by the doubling over of the edge 19, and due to the right-angle back stop portion 20, it 55 will be found that the strips will effectively retain their straight form and maintain good contact with the surface of the blotter sheet, and effectively hold the papers and memoranda in place. In this connection it is also noted that due to the slight flexibility of these strips they will tend to retain the doubled over portions 19 in face contact with the surface of the blotter sheet, but that 60 when a paper is to be set into place beneath the edge strip this can be readily done and the paper will then be held with sufficient firmness to keep it in place.

It is also noted that when using such transparent material as Celluloid or the like, it is possible to read the papers or memoranda retained by the edge strips without having to remove them, thereby greatly increasing the usefulness of the arrangement, and providing a greatly increased convenience of the user.

It is also noted that the ends of the strips coming together should be cut off at substantially forty five degrees as shown in Figure 3 in particular; and that the ends of strips which do not come into co-operation with other strips may be 5 cut off square as shown at the corner plates 11 and 14 of Figure 1. Furthermore, by terminating the edge portion 20 somewhat short of the ends of the strips as shown in Figure 1 there is provided a slightly increased flexibility of the 10 end portions of these strips, so as to make it easier to set them into place beneath the corner plates, without detracting from the effectiveness of these outer edge portions to retain the 15 papers and memoranda in place under the edge strips.

It may be noted that these edge strips may be made in sets of proper length to meet the requirements of standard sized blotter pads, and any number of the edges of the blotter pad up to its 20 entire perimeter may be provided with such strips, thereby making it possible to meet varying conditions of demand and use of such edge strip space for accommodation of the memoranda and the like. Furthermore by selecting suitable 25 colors for the edge strips very attractive and pleasing appearances thereof may be provided. The cost of manufacture of these strips will be very small.

While I have herein shown and described only 30 a single embodiment of the features of my present invention, still I do not intend to limit myself thereto, except as I may do so in the claims to follow.

I claim:

1. The combination with a blotter pad having the usual base sheet and the usual corner plates for reception of the corners of the blotter sheet thereunder, of means to provide edge supports for papers and memoranda on said blotter pad 40 and permit inspection of such memoranda while so supported and without the need of removal for such inspection, comprising removable strips of transparent slightly flexible material of proper length to extend between corner plates at one 45 edge of the blotter pad and with their end portions accommodated between such corner plates and the blotter pad and supported thereby, each such strip having its inner edge folded double to thereby reinforce such edge and with such folded 50 portion facing downwardly towards the surface of the blotter pad, and each such strip having its outer edge turned downwardly at right angles to thereby provide a back stop for papers and memoranda set into place beneath the strip, whereby 55 memoranda set into place between the strip and the surface of the blotter pad are held with edge contact of the edge portion of the strip, and whereby such memoranda may be inspected through the transparent strip and without need 60 of removal of the memoranda from the grip of the strip, substantially as and for the purpose set forth.

2. The combination with a blotter pad having the usual base sheet and the usual corner plates 65 for reception of the corners of the blotter sheet thereunder, of means to provide edge supports for papers and memoranda on said blotter pad and permit inspection of such memoranda while so supported and without the need of removal 70 for such inspection, comprising strips of transparent slightly flexible material of proper length to extend between corner plates at one edge of the blotter pad and with their end portions accommodated between such corner plates and 75

the blotter pad and supported thereby, each such strip having its outer edge turned downwardly at right angles to thereby provide a back stop for papers and memoranda set into place beneath the strip having its outer edge turned downwardly at the strip and the surface of the blotter pad are prevented from passing out from the strip at the

edge thereof opposite to such insertion, and whereby such memoranda may be inspected through the transparent strip and without need of removal of the memoranda from the support of the strip, substantially as and for the purpose set forth. 5

FRANKLIN M. DE BEERS.
